(57) CLAIM

The ornamental design for the lighting fixture, as shown and described.

DESCRIPTION

FIG. 1 is a perspective view of the lighting fixture showing my new design;

FIG. 2 is a front view thereof, the right side view, the left side view, and the rear view being the same;

FIG. 3 is a top view thereof; and,

FIG. 4 is a bottom view thereof.

Any broken line illustration of environmental structure in the drawings is not part of the design sought to be patented.
